J. E. GLOEKLER
DOOR LATCH CONSTRUCTION

Filed April 27, 1927

Patented Sept. 25, 1928.

1,685,419

UNITED STATES PATENT OFFICE.

JOHN EDWARD GLOEKLER, OF PITTSBURGH, PENNSYLVANIA.

DOOR-LATCH CONSTRUCTION.

Application filed April 27, 1927. Serial No. 186,931.

My invention refers to improvements in door construction and particularly to the latching and unlatching mechanism for refrigerator doors or the like. In such construction the door is usually heavy and of comparatively thick depth for the purpose of closing the space into a refrigerating chamber, and is mounted by heavy supporting hinges. The closure is effected by the use of 10 one or more latches of well known construction, operable by an outer handle for opening and closing as the door is swung on its hinges.

In my present improvement I utilize, in connection with such door and its framing, 15 means whereby the latch mechanism may be put into interlocking holding connection when the door is closed; means whereby the latch mechanism may be retained in an elevated free position when the door is open; 20 and means whereby the latch mechanism may be actuated from either the outside or inside, together with various features of detail construction, as shall be more fully hereinafter described.

25 In the drawings, showing one preferred embodiment of the invention:

Fig. 1 is a face view of a refrigerator door provided with the improved latching mechanism;

30 Fig. 2 is an edge view of the swinging portion of the door;

Fig. 3 is a partial inner view of the door;

Fig. 4 is an enlarged sectional view on the line IV—IV of Fig. 1.

35 Referring to the drawings, the door 2 is hung by the usual hinges 3 to one side of the door framing 4, adapting it to open and close the door opening leading to the interior of a refrigerating chamber or the like. The door 40 as shown is generally of usual construction, having an outer overlapping front portion 5 and an inner extended thickened sealing portion 6. The latter, together with the front 5 and any suitable packing or sealing devices, 45 makes close engagement with the surrounding framing of the opening, for sealing and refrigerating effect.

In the construction shown, the door when 50 closed is held by a middle bolt or arm 7 tilt- ily mounted within a housing 8 of well known construction, secured upon the outer face of the door 2, as shown in Fig. 1. Housing 8 is provided with an operating handle 9 pivoted at 10 in housing lugs, and so connected with bolt 7 that when handle 9 is withdrawn outwardly the bolt will be raised.

When the handle is released the bolt is free to fall by gravity or by spring action into or behind the hasp 11, mounted on the framing 4 for such purpose.

60 While, ordinarily, one holding bolt is sufficient for a door of average size, the door is frequently provided with several, as three, one above and one below, for further effectual latching hold. Such supplemental bolts 65 7^a are freely pivoted, as at 12, in suitable housings 13 and are adapted to interlock with similar additional hasps 14 suitably located on the surrounding frame. Such series of latching bolts in the construction shown are 70 connected for simultaneous operation by a vertically arranged bar 15 slidably mounted on holding screws 16 inserted through slots 17 thus mounting the bar for limited vertical movement on the edge of the extended portion 75 5 of the door.

Bar 15 is connected with the several bolts 7 and 7^a by extended brackets 18 having free embracing engagement around the latching bolts 7 and 7^a, as clearly shown in Fig. 2. At 80 the bottom plate 15 is connected with a spring 19, by which it is positively lowered to lower all of the bolts together, when the handle 9 is released.

85 For the purpose of providing means for opening the door from the interior, handle 9 is adapted to be actuated also from the inside. For such purpose it is provided with an inner extension lever or lug 20 against which bears the thrust rod 21 mounted transversely of the 90 door and extending through to the inside.

The inner ends of bolt 21 is pivotally connected, as at 22, with a lever arm 23. Said arm is pivotally mounted at 24 on a suitable holding bracket 25 and the lever extends 95 downwardly and inwardly at a suitable angle for depressing operation, as shown. The free end of lever 23 extends through the terminal 26 of an operating lever 27, the inner end of which is freely mounted for rotation in a 100 bracket bearing 28 on the inside of the door.

As thus arranged, arm 27 is of ample length and projects or bows around sufficiently far beyond the inner side of the door 6 to adapt it to be pressed against by the hip or knee of a 105 workman within the refrigerating chamber. When thus pressed, lever 27 and arm 23 are thrust downwardly and inwardly toward the inner face of the door, pushing against bolt 21 and thrusting lever 9 outwardly to effect 110 unlatching lifting movement of hasps 7 and 7^a, so that the door may be pushed open. The

particular advantage of the feature just described is in enabling a workman carrying a heavy load, as for instance a side of beef, to operate the latch mechanism without necessity of using either hand.

For the purpose of arresting and holding the bolt or bolts 7—7^a upwardly in raised position, upon opening the door, and for ensuring their lowering for interlocking connection with the hasps upon closing, I provide a supporting stud or trigger 29. It is slidably mounted by bolt 30 and horizontal slot 31 to the edge portion of housing 8 to ensure convenient location for coaction with the bolt. Trigger 29, as shown, is provided with an upwardly extending projection 32 adapted to engage underneath bolt 7 to support it when the door is at any open or partly open position.

Upon closing the door, the upstanding terminal 32 is thrust outwardly from underneath the bolt, allowing it to fall downwardly behind and into the off-set recess 33 of the trigger. To effect such normal supporting position, and releasing movement, I provide a stem 34 directly connected to the trigger 29 and provided with a terminal button 35 for engagement against the face of the frame 4 on closing.

A spring 36 is mounted within a housing 37, bearing inwardly therewith and outwardly against the button terminal 35, holding the trigger in supporting position, as in Fig. 4, at all times except when the door is completely closed.

When so closed, however, with sufficient force, button 35 makes contact with the framing and thrusts the trigger and its extended arm 31 outwardly from underneath the bolt 7, which thereupon drops or is pulled down behind it, effecting the desired interlocking and holding latch connection.

This latter feature is of especial advantage and importance in maintaining the bolts raised for locking connection with the hasps, avoiding the usual preliminary frictional and binding contact, while positively inserting the bolts behind the hasps only when the door is thrust into its final closing position.

The construction and operation of the invention will be readily understood and appreciated from the foregoing description, and provides a convenient, serviceable and durable latching mechanism for the purposes in view.

It will be understood that it may be changed or varied in detail construction, dimensions, number of parts, or otherwise, by the skilled mechanic, but that all such changes are to be understood as within the scope of the following claims.

What I claim is:

1. The combination with an apertured door casing and a hasp thereon, of a door pro-

vided on its outer side with a latching bolt 65 and a lifting handle therefor, a longitudinally movable operating bar for the handle extending through the door, a lever for the bar pivotally mounted on the inside of the door and pivoted to the bar, and a loosely 70 mounted horizontally arranged bowed bearing arm for said lever extending beyond the inside of the door.

2. The combination with a door provided 75 with a latching bar, of an L-shaped spring retracted arresting device for the bolt having a guiding slot, a supporting bolt therefor, and a stem adapted to disengage the bolt upon closing the door to move the stem and arresting device on its supporting bolt.

3. The combination with a door provided 80 with a latching bar, of an L-shaped spring retracted arresting device for the bolt having a guiding slot, a supporting bolt therefor, a stem connected with the arresting device 85 having a button terminal adapted to abut against a bearing surface to disengage the bolt upon closing the door, and a spring engaging the button terminal.

4. The combination with a door framing 90 and a hasp thereon, of a latching bolt on the door provided with an operating handle, and an L-shaped supporting abutment for the latching bolt having a guiding slot, a pin 95 therefor, and a spring actuated retracting stem connected with the abutment provided with a terminal adapted to engage the frame when the door is closed to release the latching bolt.

5. The combination with a door framing 100 and a hasp thereon, of a pivoted vertically movable latching bolt on the door provided with an operating handle, and a slidably mounted off-set L-shaped supporting abutment for the latching bolt having a guiding slot, a supporting bolt therefor, and a spring actuated retracting stem for the abutment 105 provided with a terminal adapted to engage the frame when the door is closed to release the latching bolt.

6. The combination with a door framing and a plurality of hasps thereon, of a plurality of latching bolts on the door for engagement with said hasps, a connecting bar having slotted connection with all of said bolts for operation together, an operating handle for one of said bolts, a slidably mounted L-shaped supporting abutment for the latching bolt having a guiding slot, a supporting bolt therefor, and a spring retracted 115 stem for the abutment provided with a terminal adapted to engage the frame when the door is closed to release the said latching bolt and the other bolts connected therewith.

In testimony whereof I hereunto affix my 120 signature.

JOHN EDWARD GLOEKLER.
